UNITED STATES PATENT OFFICE

ANDREW DORDAN AND ELMINA JOHNSON, OF MINNEAPOLIS, MINNESOTA

DESIGN FOR A HOME ALTAR

Application filed March 18, 1931. Serial No. 39,139. Term of patent 3½ years.

To all whom it may concern:

Be it known that we, ANDREW DORDAN and ELMINA JOHNSON, citizens of the United States, residing at Minneapolis, in the county of Hennepin and State of Minnesota, have invented a new, original, and ornamental Design for Home Altar, of which the following is a specification, reference being had to the accompanying drawing, forming part thereof, wherein is shown a perspective view of a home altar embodying our design. The ornamental design as illustrated comprises a rectangular parallelepiped having an un-

decorated plane rear wall and having the decorative design elements, as clearly shown in the drawing, on its front vertical wall. The vertical corners or edges at the front of the parallelepiped are provided with the ornamental mounting as clearly shown in the drawing.

What we claim is:

The ornamental design for a home altar, substantially as shown and described.

ANDREW DORDAN.
ELMINA JOHNSON.
